CARBURETOR CONSTRUCTION

André Roualet, Detroit, Mich., assignor to Chrysler Corporation, Detroit, Mich., a corporation of Delaware

Application May 13, 1929, Serial No. 362,614

22 Claims. (Cl. 261—50)

This invention relates to carburetor construction.

The main objects of my invention are to provide an improved carburetor having a vaporizing chamber therein in which a supply of gasoline is admitted to the vaporizing chamber when the choke valve of the carburetor is closed, and to provide an improved construction of butterfly choke valve wherein an auxiliary air inlet is opened against yielding pressure by suction from the engine.

An illustrative embodiment of this invention is shown in the accompanying drawing, in which:

Fig. 1 is a view in side elevation of the improved carburetor, a portion thereof being shown in vertical section, taken on the line 1—1 of Fig. 2.

Fig. 2 is a sectional view taken on line 2—2 of Fig. 1.

Fig. 3 is a fragmentary, vertical medial sectional view of the improved butterfly choke valve mounted in a carburetor air inlet.

Fig. 4 is a fragmentary view, partly in elevation and partly in vertical section, of a modified construction showing my improved means for admitting gasoline to the fumer chamber.

Heretofore in the construction of carburetors equipped with auxiliary vaporizing chambers there has been some difficulty encountered in the matter of having a supply of gasoline present in the fumer chamber when the choke is closed and the electrical connections made. In the past the supply of gasoline to the fumer chamber was dependent upon flooding of the carburetor and sometimes such flooding was insufficient to provide the proper amount of gasoline to the fumer.

In the present construction means are provided whereby a supply of gasoline is always admitted to the fumer chamber when the carburetor is choked as long as there is a supply in the carburetor float chamber.

In the construction shown in the drawing, the carburetor comprises the customary float chamber 5, which has communication to the main needle valve control 6. An air inlet 7 communicates with the mixing chamber 8 which surrounds the needle valve 6 in the customary manner.

A vaporizing chamber 9 is located adjacent the mixing chamber 8 and has communication therewith, said vaporizer chamber being provided with an electrical heating element 10, to which an electrical connection is made through a binding post 11 located at the lower end thereof.

The float chamber 5 is provided with a discharge passageway 12 adjacent the lower end

thereof, which is controlled by an auxiliary needle valve 13 normally held closed on its seat by a helical compression spring 14 which surrounds the upper end of the needle valve 13 and bears between a cover plate 15 and a washer 16 secured by a pin 17 mounted transversely and medially of the valve 13.

Means are provided for raising the needle valve 13 from its seat when the choke to the carburetor is closed and comprises a lever 18 pivotally mounted on the stud 19, one end of which engages the under side of a cap 20 mounted on the upper protruding end of needle valve 13, and the other end of which is engaged by a cam 21 mounted on the outer protruding end of a shaft 22 which carries a butterfly choke valve 23. Gasoline passing from the float chamber through the discharge passageway 12 and by the valve 13 mixes with air in the space around the needle valve 13 and then passes through a passageway 24 to a vertically disposed passageway 25, the upper end of which communicates with the mixing chamber of the carburetor.

Means are provided for admitting gasoline from the passageways 24 and 25 into the vaporizing chamber 9 and comprises a passageway 26 drilled in alignment with the passageway 24. The inner end of the passageway 26 adjacent the vaporizing chamber 9 is preferably restricted by a threaded plug 27, which has a small aperture bored there through, preferably by a No. 70 drill.

The butterfly choke valve 23 has an air passageway 28 therethrough formed partially at each side of the shaft 22 which carries said valve. An auxiliary valve 29 is journaled on the shaft 22 and is adapted to close the air passageway 28 when rotated to a closed position. A spring 30 is attached at one end by screws 31 to the valve 23, the other end of said spring bearing against the auxiliary valve 29 for normally yieldingingly urging said auxiliary valve to a closed position.

In the modification shown in Fig. 4 of the drawing, the vaporizing chamber 9 is shown located at a lower level than in the construction shown in Figs. 1 and 2 and in this modified construction the lower end of the vertically disposed passageway 25 is counterbored and provided with a plug 32, through which is drilled a restricted orifice, preferably by a No. 70 drill. A chamber 33 is provided below the plug 32, which in turn communicates with the vaporizing chamber 9 by a passageway 34. The lower end of the counterbore is closed by a threaded plug 35 screwed thereinto.

In the operation of this improved carburetor

- the auxiliary or choke needle valve 13 is normally closed on its valve seat by the compression spring 14 so that gasoline from the float chamber 5 will not be admitted to the passageways 24 and 25.
- 5 Upon closing of the butterfly choke valve 23, the cam 21 rocks the lever 18 on its pivot 19 so as to engage the underside of the head 20 secured to the top end of the needle valve 13 and thereby raise said valve from its seat. Opening of the 10 valve 13 from its seat permits gasoline from the float chamber to flow through the discharge passageway 12 and past the valve 13 where it is mixed with air and drawn into the passageways 24 and 25 by suction from the engine.
- 15 At the same time a small amount of gasoline will enter the passageway 26 and through the restricted opening in the threaded plug 27 into the auxiliary vaporizing chamber 9, thereby supplying the fumer with the correct amount of gasoline 20 for proper operation thereof.
- 20 In order to prevent over-choking of the carburetor when the butterfly valve 23 is fully closed, the tension on the spring 30 is such that the auxiliary valve 29 will open by suction and permit 25 the passage of air into the carburetor, the amount of such air being in direct proportion to the amount of suction to which the valve is subjected.
- The opening of the auxiliary valve is proportional 30 to the suction and the degree of opening is predetermined by the tension of the spring 30 so as to provide for the admission of the correct amount of air required to mix with the fuel introduced into the system while the choke valve is closed. In this manner, the air and fuel components of the mixture are controlled so as to produce a fuel mixture having suitable explosive 35 properties for starting and warming up an internal combustion engine. The freedom of the auxiliary valve to open when the choke is fully closed, as well as when it is partially opened, renders it effective in controlling the air factor 40 of the fuel mixture during initial starting, follow through, and warming up stages of the engine.
- Although but one specific embodiment and one 45 modification of this invention have been herein shown and described, it will be understood that numerous details of constructions shown may be altered or omitted without departing from the spirit of my invention as defined by the following 50 claims.
- What I claim is:
1. The combination, in a carburetor of the class described having a mixing chamber and an independent auxiliary vaporizing chamber, a float 55 chamber and a choke valve, of means operative by the closing of said choke valve for permitting fluid from said float chamber to pass to said vaporizing chamber only when said choke valve is closed.
- 60 2. In a carburetor, a float chamber having an outlet passageway adjacent the lower end thereof, a vaporizing chamber having a fumer therein, a passageway providing communication between said fumer chamber and said outlet passageway, 65 a valve in said outlet between said passageway and said float chamber, choke connections on said carburetor, and means operated by said choke connection for opening said valve only when said choke is closed.
- 65 3. In a carburetor having a choke valve, a vaporizing chamber having a fumer therein, a source of fuel, a passageway providing communication between said vaporizing chamber and the source of fuel, a fumer valve for controlling 70 said passageway, and connections be-
- tween said fumer valve and said choke valve for opening said fumer valve only when said choke valve is closed.
4. In a carburetor having a mixing chamber and a fuel system for feeding fuel thereto during normal running operations including a fuel reservoir, a choke valve in the air inlet of said mixing chamber, an auxiliary starting fuel system communicating with said fuel reservoir and mixing chamber and including a vaporizing chamber, a fuel valve for controlling the flow of fuel from said reservoir into said starting fuel system, and means for operating said choke valve and said fuel valve in timed relation so as to open the latter only when said choke valve is closed. 5
5. In a carburetor having a mixing chamber and a fuel system for feeding fuel thereto during normal running operation, a choke valve in the air inlet of said mixing chamber, a source of fuel in communication with the normal fuel system, 10 an auxiliary fuel system communicating with said source of fuel and communicating with the mixing chamber independently of said normal fuel system and including a vaporizing chamber, a fuel valve for controlling the flow of fuel to said auxiliary fuel system independently of said normal fuel system, and means for operating said choke valve and said fuel valve in timed relation so as to open the latter only when said choke valve is closed. 15
6. In a carburetor having a mixing chamber and a fuel system for feeding fuel thereto during normal running operation, a choke valve in the air inlet of said mixing chamber, a source of fuel in communication with the normal fuel system, 20 an auxiliary fuel system communicating with said source of fuel and communicating with the mixing chamber independently of said normal fuel system and including a vaporizing chamber, a fuel valve for controlling the flow of fuel to said auxiliary fuel system independently of said normal fuel system, and means for operating said choke valve and said fuel valve in timed relation so as to open the latter only when said choke valve is closed. 25
7. In a carburetor having a mixing chamber and a fuel system for feeding fuel thereto during normal operation, a source of liquid fuel communicating with said mixing chamber, an auxiliary fuel system having a vaporizing chamber communicating with said mixing chamber and with said source of fuel, a heating element in said vaporizing chamber, said auxiliary fuel system having a passage communicating with said mixing chamber independently of said vaporizing chamber, and a fuel valve in said auxiliary fuel system for rendering the same operative only 30 during starting of an engine. 35
8. In a carburetor having a mixing chamber and a fuel system for feeding fuel thereto during normal operation, a source of liquid fuel communicating with said mixing chamber, an auxiliary fuel system having a vaporizing chamber communicating with said mixing chamber and with said source of fuel, a heating element in said vaporizing chamber, said auxiliary fuel system having a passage communicating with said mixing chamber independently of said vaporizing chamber, a choke valve in the inlet of said mixing chamber, a fuel valve in said auxiliary fuel system for controlling the flow of fuel to said vaporizing chamber and to said passage, and means 40 operable by the closing of said choke valve for 45
9. In a carburetor having a mixing chamber and a fuel system for feeding fuel thereto during normal operation, a source of liquid fuel communicating with said mixing chamber, an auxiliary fuel system having a vaporizing chamber communicating with said mixing chamber and with said source of fuel, a heating element in said vaporizing chamber, said auxiliary fuel system having a passage communicating with said mixing chamber independently of said vaporizing chamber, a choke valve in the inlet of said mixing chamber, a fuel valve in said auxiliary fuel system for controlling the flow of fuel to said vaporizing chamber and to said passage, and means 45 operable by the closing of said choke valve for 50
10. In a carburetor having a mixing chamber and a fuel system for feeding fuel thereto during normal operation, a source of liquid fuel communicating with said mixing chamber, an auxiliary fuel system having a vaporizing chamber communicating with said mixing chamber and with said source of fuel, a heating element in said vaporizing chamber, said auxiliary fuel system having a passage communicating with said mixing chamber independently of said vaporizing chamber, a choke valve in the inlet of said mixing chamber, a fuel valve in said auxiliary fuel system for controlling the flow of fuel to said vaporizing chamber and to said passage, and means 55 operable by the closing of said choke valve for 60
11. In a carburetor having a mixing chamber and a fuel system for feeding fuel thereto during normal operation, a source of liquid fuel communicating with said mixing chamber, an auxiliary fuel system having a vaporizing chamber communicating with said mixing chamber and with said source of fuel, a heating element in said vaporizing chamber, said auxiliary fuel system having a passage communicating with said mixing chamber independently of said vaporizing chamber, a choke valve in the inlet of said mixing chamber, a fuel valve in said auxiliary fuel system for controlling the flow of fuel to said vaporizing chamber and to said passage, and means 65 operable by the closing of said choke valve for 70
12. In a carburetor having a mixing chamber and a fuel system for feeding fuel thereto during normal operation, a source of liquid fuel communicating with said mixing chamber, an auxiliary fuel system having a vaporizing chamber communicating with said mixing chamber and with said source of fuel, a heating element in said vaporizing chamber, said auxiliary fuel system having a passage communicating with said mixing chamber independently of said vaporizing chamber, a choke valve in the inlet of said mixing chamber, a fuel valve in said auxiliary fuel system for controlling the flow of fuel to said vaporizing chamber and to said passage, and means 75 operable by the closing of said choke valve for 80

opening said fuel valve so as to supply fuel to said passage and vaporizing chamber during starting of an engine.

9. In a carburetor having a mixing chamber and a conventional fuel feeding system for supplying fuel thereto during normal carburetor operation, a choke valve for controlling the flow of air through said mixing chamber having an opening therein, an auxiliary fuel system for feeding fuel independently of said normal fuel system to said mixing chamber during commencement of the operation of said carburetor and including a fuel valve, valve actuating mechanism operable by said choke valve for opening said fuel valve when said choke valve is closed, and yieldable means operable by the suction in said mixing chamber for regulating the flow of air through the opening in said choke valve during the starting stage of the operation of said carburetor.

10. In a carburetor having a mixing chamber and a conventional fuel feeding system for supplying fuel thereto during normal carburetor operation, a choke valve for controlling the flow of air through said mixing chamber having an opening therein, an auxiliary fuel system for feeding fuel independently of said normal fuel system to said mixing chamber during commencement of the operation of said carburetor and including a fuel valve, a vaporizing chamber in said auxiliary fuel system having a fumer therein, valve actuating mechanism operable by said choke valve for opening said fuel valve when said choke valve is closed, and yieldable means operable by the suction in said mixing chamber for regulating the flow of air through the opening in said choke valve during the starting stage of the operation of said carburetor.

11. In a carburetor having a mixing chamber and a fuel system for feeding fuel thereto during normal carburetor operation, a source of fuel communicating with said mixing chamber, an auxiliary fuel system having a vaporizing chamber communicating with said mixing chamber and with said source of fuel and including a passageway communicating with said mixing chamber and having an air bleed, means for metering the flow of fuel to said vaporizing chamber, a valve in said auxiliary fuel system for controlling the flow of fuel to said passageway and to said vaporizing chamber, a choke valve having an opening therein located in the inlet to said mixing chamber, control means for said fuel valve operable by said choke valve so as to permit fuel to flow to said passageway and vaporizing chamber when said choke valve is closed, and a yieldable member on said choke valve operable by the suction of said carburetor for metering the flow of air through said choke valve when the latter is closed to correspond with the flow of fuel to said passageway and vaporizing chamber so as to provide a starting mixture having a predetermined fuel ratio.

12. In a carburetor having a mixing chamber, a fuel reservoir and a normal fuel system for feeding fuel thereto during normal running operation, an auxiliary starting fuel system communicating with said mixing chamber independently of said normal fuel system and with said reservoir, and means governing the flow of fuel to said auxiliary fuel system for rendering the latter operative only when said carburetor is conditioned for starting.

13. In a carburetor having a mixing chamber and a normal fuel system for feeding fuel thereto

during normal running operation, an auxiliary starting fuel system communicating with said mixing chamber independently of said normal system, and means for alternatively conditioning said carburetor for starting and normal operations respectively including a valve in said auxiliary fuel feeding system for permitting a flow of fuel thereto only when said carburetor is conditioned for starting.

14. A carburetor including a mixing chamber having an air inlet, a normal fuel system communicating with said mixing chamber for feeding fuel thereto during normal running operation, an auxiliary starting fuel system communicating with said mixing chamber, a normally closed fuel valve in said auxiliary fuel system for controlling the admission of fuel thereto, means for conditioning the air factor of said carburetor for starting, and apparatus for opening said fuel valve only when said means is operative.

15. A carburetor including a mixing chamber having an air inlet, a choke valve in said air inlet for conditioning said carburetor for starting, a normal fuel system communicating with said mixing chamber for feeding fuel thereto during normal running operation, an auxiliary starting fuel system communicating with said mixing chamber, a fuel valve in said auxiliary fuel system, apparatus for opening said fuel valve only when said carburetor is conditioned for starting by said choke valve, and yieldable means operable by the suction in said mixing chamber for controlling the supply of air thereto during starting.

16. In a carburetor having a mixing chamber and a fuel system for feeding fuel thereto during normal running operations including a fuel reservoir, a choke valve in the air inlet of said mixing chamber, an auxiliary starting fuel system communicating with said fuel reservoir and mixing chamber, a fuel valve for controlling the admission of fuel from said reservoir into said starting fuel system, and means for operating said choke valve and said fuel valve in timed relation so as to open the latter only when said choke valve is closed.

17. A carburetor for an internal combustion engine including a passage for supplying fuel mixture to the latter and having an air inlet, a choke valve in said air inlet for conditioning said carburetor for starting and having an opening therein, a normal fuel system communicating with said passage for feed fuel thereto during normal running operation, an auxiliary starting fuel system communicating with said passage, a fuel valve in said auxiliary fuel system, apparatus for opening said fuel valve only when said carburetor is conditioned for starting, and yieldable means operable by the suction in said passage for regulating the flow of air through the opening in said choke during the starting stage of the operation of said carburetor.

18. A carburetor for an internal combustion engine including a passage for supplying fuel mixture to the latter and having an air inlet, a choke valve in said air inlet for conditioning said carburetor for starting and having an opening therein, a normal fuel system communicating with said passage for feed fuel thereto during normal running operation, an auxiliary starting fuel system communicating with said passage, having an air bleed for mixing air with the fuel therein prior to its admission to said passage, a fuel valve in said auxiliary fuel system, apparatus for opening said fuel valve only when said carburetor is

- conditioned for starting, and yieldable means operable by the suction in said passage for regulating the flow of air through the opening in said choke during the starting stage of the operation of said carburetor.
5. 19. In a carburetor having a mixing chamber and a fuel system for feeding fuel thereto during normal operation, a fuel reservoir communicating with said mixing chamber, a vaporizing chamber communicating with said mixing chamber, a heating element in said vaporizing chamber, an auxiliary fuel system having a passage communicating with said reservoir and with said vaporizing chamber for delivering fuel to said heater and having a passage for supplying to said mixing chamber fuel in addition to that delivered to said heater, and a fuel valve in said auxiliary system for controlling the flow of fuel to both of said passages and rendering the auxiliary system operative only during starting of an engine.
10. 20. In a carburetor having a mixing chamber and a fuel system for feeding fuel thereto during normal operation, a fuel reservoir communicating with said mixing chamber, a vaporizing chamber communicating with said mixing chamber, a heating element in said vaporizing chamber, an auxiliary fuel system including a passage having an air inlet and communicating with said reservoir and with said vaporizing chamber for delivering fuel to said heater and having a passage for supplying a mixture of fuel and air to said mixing chamber, and means for opening said fuel valve only during starting of an internal combustion engine.
15. 21. In a carburetor having a mixing chamber and a fuel system for feeding fuel thereto during normal operation, a fuel reservoir communicating with said mixing chamber, a vaporizing chamber communicating with said mixing chamber, a heating element in said vaporizing chamber, an auxiliary fuel system including a passage having an air inlet and communicating with said reservoir and with said vaporizing chamber for delivering fuel to said heater and having a passage for supplying a mixture of fuel and air to said mixing chamber, and means for opening said fuel valve only during starting of an internal combustion engine.
20. 22. In a carburetor having an air inlet, a choke valve for controlling said air inlet, a vaporizing chamber having a fumer therein, a source of fuel, a passageway providing communication between the source of fuel and said chamber for supplying fuel to said fumer, a fuel valve for controlling said passageway, and means for opening and closing the latter valve when the choke valve is closed and opened respectively.
